METHOD FOR TREATING OIL

Arthur J. Slagter and Charles W. MacKay, Tulsa,
Okla., assignors to The Ohio Oil Company,
Findlay, Ohio, a corporation of Ohio

Application December 4, 1931, Serial No. 578,964

2 Claims. (Cl. 196—73)

This invention relates to improvements in methods of and apparatus for manufacturing petroleum products. The invention may be usefully applied not only in primary refining or processing operations, but also in the refining, reduction or processing of derivatives or intermediates products emerging from the primary operations.

The method invention, in its broad aspects, may be practiced in connection with a wide variety of oil heating or vaporizing devices or systems.

The invention may be employed for the production of superior grades of straight run and cracked gasoline and naphtha; to procure increased yield of kerosene; to produce a more readily pressable wax distillate, more readily treatable medium and heavy distillates, and superior grades of gasoline by the refining of raw gasoline; to produce an effective solvent material from raw kerosene or other sources; for the production of solvent materials and kerosene from gas oil or other sources; and for the production of lubricating stocks generally from lubricating distillates or other sources. In general, an object of our invention has been to improve the quality of petroleum products derived from known raw materials and to increase the number and improve the quality of petroleum products producible from crudes and/or intermediates.

In general the practice of our method invention involves subjecting crude petroleum or some derivative thereof to sufficient heat in stages to produce selective vaporization under predetermined conditions of pressure or vacuum, separating the vapor from the liquid, subjecting the entire amount of the vapor separated under any selected condition to a superheating treatment involving the application of temperatures, selected appropriately to the results sought, and subsequently subjecting the selectively separated and superheated vapors to cooling operations which vary according to the character or quality, or both, of the product desired. With such a method resulting condensates may be removed as ultimate products or may be returned to various parts of the processing apparatus for retreatment, this portion of the method being intended more particularly to produce a predetermined product by the retreatment of an intermediate

product, for example, in a continuous system and in a continuous operation.

An exemplary form of apparatus for practicing the method invention and embodying the mechanical invention, is illustrated in the drawing accompanying the present specification, and in which,

Figure 1 is a general view in perspective; and Figure 2, an enlarged detail in perspective illustrating schematically a typical arrangement of discharge and connecting pipes or conduits associated with the reaction and bubble towers.

Referring to the drawing, the apparatus shown in Figure 1 comprises a plurality of stills 1, 2, and 3, or any other suitable number thereof, each, in the illustrated embodiment, being in the form of a cylindrical tank or shell, the under side of which provides in effect the top wall of a furnace of any suitable construction. Each furnace has vapor superheating means, including, for example, a plurality of pipes 9, communicating with headers 10, the upper or inlet ends of which open into the interior of the respective stills above their respective levels of unvaporized liquid to receive vapors generated therein and convey the same to be superheated in said pipes 9.

The charge to be treated, such for example, as crude petroleum, lubricating distillate or other intermediate or appropriate petroleum compound, is introduced into the illustrative system by charging devices including a pump 11 and a pipe 12, of which a portion forms a coil 13 of a heat exchanger including a tank 14, to the interior of which is supplied a hot product, such for example as residuum from the stills 1, 2, 3, etc. The charge is conducted through the pipe 12 to coils 16 each of which is enclosed in a tower 17 forming part of a combination vapor heat exchanger and reaction chamber in which said coils are exposed to heated or superheated vapors or other heated products or intermediates also from said stills. From one or more of the coils 16 in towers 17, the charge is moved through pipe 18 and discharged by pipe 18a into still 1, for example. An outlet pipe 19 receives liquid flowing out from the interior of still 1 which outflow may be fed by means of an interstage pump 20 into still 2.

The inlet and outlet conduits or pipes hereinabove described in connection with stills 1 and 2

and the pump 20 are duplicated if desired in connection with the remaining stills in the battery, it being noted, however, that the conduits for still 3 communicate with the interior of said still 5 at a lower level than that at which the corresponding pipes or conduits communicate with their respective stills 1 and 2; and that, in relation to this arrangement of the inlet and outlet conduits, a liquid level gradient is provided 10 ranging from a relatively high level in still 1 to a relatively low level of material treated in the still 3. A similar or other suitable gradient may be provided in a further succession of like stills.

With the arrangement just described for introducing the charge into the stills, the oil to be treated reaches the first still at a relatively high temperature and is there subjected to the direct heat of the furnace. Under some conditions, the vaporization or other reaction may be 20 accompanied by the introduction of steam or superheated steam or both into the still. It may be introduced for some purposes into the upper portion of the still, namely the space above liquid level through a steam pipe 21. It may also be 25 introduced into the still preferably in the form of steam sprays liberated within the body of the liquid and preferably in the vicinity of the bottom of the still by means of a pipe 22. Thus, in one case, namely where steam is introduced 30 through pipe 21, it reacts directly with the vaporized liquid; and in the other case, namely where it is introduced through pipe 22, the steam reacts with the material in liquid form.

In operation, the initial charge enters still 1. 35 A predetermined portion thereof or the more volatile components of the charge separate therefrom in said still in the form of vapor and/or gas all of which is withdrawn downwardly through the openings in the tops of headers 10, 40 said vapors being then superheated in the pipes 9 and thence discharged through pipes 23 and 45 into heat exchange and/or condensation apparatus hereinafter to be described. A predetermined level of liquid in still 1 is maintained by outflow of said liquid through discharge pipe 19, 50 this operation being facilitated by the pump 20; although, if desired and if conditions warrant, a similar control or movement may be effected by gravity or by causing or maintaining differential pressures in the different stills. Thus, by 55 closing valves 24, 24, for example, the flow of liquid from outlet pipe 19 of still 1 to the inlet 18a of still 2 by-passes pump 20 and is effected through pipe 25. However, by closing valve 26 60 in pipe 25, and opening valves 24, 24, the discharge or outflow from still 1 will pass through pump 20 and thence to still 2 or some other selected still.

Control of the course of fluid supplied to still 60 1 is further effected by means of valves 27 and 28 in pipes 18a and 19 respectively and by valve 29 interposed in a connection between said pipes 18a and 19. For example, to secure circulation 65 of fluid inwardly through pipe 18a and outwardly through pipe 19, valve 29 is closed and valves 27 and 28 are opened. By closing valves 27 and 28, and opening valve 29, the charge is by-passed as to any selected still or stills, and may be admitted into any other selected still or stills, depending upon a variety of circumstances including 70 the character or yield of the product desired.

Assuming that circulation has been established 75 through any predetermined number of stills and that the desired products have been thereby re-

covered, the residuum is withdrawn from the last still of any selected series by means of a pipe 30, which discharges directly into the tank 14 so that some of the heat carried by said residuum is applied to the incoming charge of oil or other material as it circulates through the coil 13 previously referred to. The residuum is then discharged from tank 14 by means of a pipe 31 and thereby conducted to storage, or otherwise disposed of. 10

For convenient operation and effective control of the product, the connections between each still and its corresponding heat exchange, or condensation or fractionation devices may be and preferably are the same as those of each 15 other still; and the condensation devices are preferably interconnected in such a way that the discharge therefrom may be removed as a completed product and/or may be reintroduced into the treating operation at any desired portion 20 thereof. Thus, each of the vapor outlet pipes 23 discharges into a bottom portion of a tower 17, the interior of which is cooled in part by means of the coil 16 carrying the relatively cool charging liquid and in part by back trap condensate 25 as hereinafter described. The condensation product in said tower 17 is withdrawn through a pipe 32 which is controlled by a valve 33, shown more clearly in Figure 2, said pipe 32 having a portion in the form of a gooseneck or trap 34 30 from which the product may be discharged through an outlet pipe 35 by opening a valve 36; or, by closing valve 36, the product may be returned to still 1 through pipe 37 controlled by valve 38. Another pipe 39 which connects with 35 pipe 37 includes a valve 40. When valve 40 is open, the outflow through pipe 39 together with that through pipe 37 discharges into the still 1.

When valve 40 is closed the condensate coming from pipe 32 or a portion thereof may be discharged into one or both of the pipes 41 and 42, 40 past valves 43 and 44, these pipes being the common connecting pipes utilized as interconnections between the vapor heat exchanger or condensation devices of the several stills. If desired, 45 a pump 45 is connected to either or both of the pipes 41 and 42 in such a way that the condensate therein can be moved by the pump or can bypass the pump as circumstances may determine. Thus, valves 46 and 47 control the input to pump 50 45 from pipes 41 and 42 respectively, and valves 48 and 49 control the output from pump 45 into the pipes 41 and 42. A valve 50 in pipe 41 may be opened to permit flow of condensate past the pump 45 if desired and a valve 51 performs a similar function in respect to the flow of liquid through pipe 42 past pump 45.

The connections and control valves just described may be repeated in respect to each still and its vapor heat exchanger if desired, to the 60 end that the back trap return from any exchanger may be withdrawn and/or reintroduced into any still or stills in addition to the original charge or any portion thereof.

An additional cooling effect is attained in the 65 tower 17 by supplying thereto the back trap return condensate or a portion thereof from a further or more remote cooling or condensing operation, taking place for example in a fractionating 70 column or bubble tower 52. The product of any such column may be withdrawn directly as a completed product through a pipe 53 communicating with an outlet pipe 54 at the bottom of column 52; or the whole or a part of said product may be re- 75

turned to a selected still either directly through a pipe 55 or indirectly through a branch pipe 56 to the tower 17 and thence to a still, said pipes being provided with suitable valves for permitting 5 the alternative modes of operation above stated. For example, the pipe 56 has a valve 58 which, when closed, prevents the circulation of fractionating column back trap return in the branch which includes the pipe 56. A valve 59 in pipe 10 55 may be utilized to control the flow of fractionating column back trap return to the still. For example, when valve 59 is closed and valve 58 is open, the condensate in pipe 55 operates as a 15 vapor cooling medium in the tower 17 and is discharged therefrom through pipe 32.

Fixed gases and uncondensed vapors pass from the tower 17 through a pipe 60 into a lower portion of the bubble tower or fractionating column 20 52. Any suitable reflux may be pumped or otherwise introduced into said column through the pipe 61. The uncondensed vapors and/or fixed gases in the fractionating column 52 are delivered through a pipe 62 to suitable condensers or receivers or both, not shown.

In some cases, it may be desirable to provide means whereby the bubble tower or fractionating column may be by-passed or used for its ordinary intended purpose at will. In such case, the inlet pipe 60 and the outlet pipe 62 are connected by a pipe 63 containing a valve 64. A valve 65 is interposed between the pipe 60 and the fractionating column 52, and a valve 66 between the fractionating column and the outlet pipe 62. Thus, when valves 65 and 66 are closed and valve 64 is open, the vapor product discharged from the vapor heat exchanger passes out directly through outlet pipe 62.

40

Simultaneously and continuously with vaporizing, the entire vaporized portions of the charging stock are independently withdrawn and superheated and then treated in the reaction and/or fractionation towers connected with the several 5 stills; and the condensates in these towers are selectively disposed of to suit a wide range of conditions. It will be apparent that, depending upon the conditions of temperature, pressure, vacuum and/or steam employed, the apparatus operates 10 interchangeably and, if desired, simultaneously both as a straight distillation apparatus and/or as a cracking apparatus.

Where we utilize a system employing a battery 15 of eight stills, for example, operating at temperatures and pressures which produce cracking, at least 70% by weight of the treated liquid is reduced to vapor form, the remainder issuing from the last still as a heavy fuel residuum. This vaporization takes place by stages in the several 20 stills, the entire amount of vapors produced in each still being separated from the liquid and conducted through a superheating zone to undergo such superheating treatment as conditions 25 require.

The range of utility of our improved apparatus will be better understood by reference to a disclosure of typical operating conditions and the products recovered in connection therewith.

30

Primary distillation of paraffinic crude

In employing our system, comprising a battery of eight stills and corresponding reaction and bubble towers, for example, as a distillation apparatus more particularly for handling a crude having a paraffine base, typical operating conditions are indicated by reference to the following tabulation:

35

Still No.	Still temp.	Vapor temp. leaving super-heater (23)	Temp. bottom of combination reaction chamber heat exchanger tower (17)	Temp. top of combination tower (17)	Temp. bottom of bubble tower (52)	Temp. top of bubble tower (52)	Pressure in still #/gauge sq. in.
45							45
50	1 450°	650°	550°	500°	460°	300°	Approximately
	2 500	700	600	550	510	365	Atmo.
	3 550	725	625	575	535	425	Atmo.
	4 600 (steam)	750	635	585	545	450	Atmo.
	5 650 (steam)	800	650	600	560	475	Atmo.
	6 700 (steam)	850	700	650	610	500	Atmo.
	7 750 (steam)	900	750	700	660	525	Atmo.
	8 800 (steam)	950	800	750	710	550	Atmo.

40

55 As previously suggested, the back trap return from the fractionating column 52 may be utilized in a manner similar to that of the back trap return from the reaction heat exchanger towers 17 and by a similar arrangement of pipe connections and valve controls. Furthermore, the same type of interstage pumping devices and valve control apparatus may also be utilized in connection with the fractionating columns 52 as has been described in connection with the towers 17.

60 The apparatus above described provides an oil processing system in the operation of which a suitable charging stock is passed in a continuous stream through a sequence of any desired number of vaporizing stills. Where desired, the vaporizing temperature in each still may be different from that of each other still; and likewise, the vapor superheating temperatures may vary 65 according to any desired or predetermined plan.

65 It will be noted in the foregoing tabulation that the introduction of steam is indicated in stills numbers 4 to 8 inclusive. Under the specified conditions of operation, steam is introduced in liberal quantities more particularly in those stills from which wax distillates and lubricating stock residuum respectively are to be recovered. Naturally, these products appear toward the end of the sequence of the stills, being derived from vapors of 70 heavier consistency than other vaporizable products of the operation, such as light gasoline, heavy gasoline, naphtha, kerosene and gas oil. Where a liberal amount of steam is indicated, we have in mind about 200 pounds per barrel of 75 charge.

In another use of our improved apparatus, we contemplate the employment of a vacuum more particularly in various of the end stills of 75

the sequence. Typical operating conditions are set forth in the following tabulation:

5	Still No.	Still temp.	Vapor temp. leaving superheater (23)	Temp. bottom of combination reaction chamber heat exchanger tower (17)	Temp. top of combination tower (17)	Temp. bottom of bubble tower (52)	Temp. top of bubble tower (52)	Pressure in still #/gauge sq. in.	5
10	1	450°	650°	550°	500°	460°	300°	Approximately Atmo.	10
	2	500	700	600	550	510	365	Atmo.	
	3	550	725	625	575	535	400	Atmo.	
	4	600 (steam)	750	625	575	540	420	Atmo.	
	5 (vac)	625 (steam)	765	625	575	540	440	28 inches Hg. vacuum.	
15	6 (vac)	650 (steam)	775	650	600	560	460	Do.	15
	7 (vac)	675 (steam)	785	675	625	585	480	Do.	
	8 (vac)	700 (steam)	800	700	650	610	500	Do.	

With the foregoing temperatures, pressures and other factors, the yields include gasoline, naphtha, kerosene, gas oil, wax distillate, one or more intermediates in the form of lubricating distillates derived from an overhead condensed vapor in each instance. The residuum is a tarry mass containing no lubricating material. In connection with the operation of still No. 5 under a vacuum which takes place preferably after part of the gas oil has been taken off, the vacuum is rendered effective by application to the condensing system of the still or stills, and may be produced by any suitable or well known means such as jet pumps, vacuum exhausters or the like, not specifically shown. The steam is utilized as in the operations represented in the previous tabulation.

Primary distillation of naphthenic crudes

For distillation of naphthenic crudes, we utilize substantially the operating conditions hereinabove set forth in connection with our discussion of the distillation of paraffinic crudes. The products include light gasoline, heavy gasoline, naphtha, gas oil, a series of naphthenic lubricating distillates and an asphaltic residuum. Here again we employ liberal amounts of steam in those stills from which the lubricating distillates are recovered.

By employing vacuum in the latter stages of the operation of processing the naphthenic crude, relatively greater quantities of the three lubricating distillates are obtained while the quantity of gas oil yield is reduced. In this operation, the amount of steam used may be reduced to around 25 pounds per barrel of charge treated and the vac-

vaporized out of the liquid charge at a lower temperature than would otherwise be required,

thereby producing less risk of cracking, which is detrimental to the viscosity of the product.

Rerunning lubricating distillates before chemical treatment

Our processing system is also adapted to advantageously treat lubricating distillates after they have been recovered from the crude by primary distillation of whatsoever character and before any chemical treatment. For this purpose, we utilize the range of temperatures indicated in the foregoing tabulations and employ liberal amounts of steam in the stills with vacuum in the latter stages. By this operation we effect distillation of the charge without cracking beyond the degree permitted for producing a proper lubricating oil, and effect a change in the character of the impurities in the charge, which permits them to be removed more readily and at less expense by subsequent treatment. While the exact nature of these changes is not fully understood, it is our view that the wax and petrolatum contents are made more crystalline by superheating in the vapor stage and the mercaptan and other heavier impurities are so affected by the superheating that their removal requires less acid and a shorter time of treatment.

Cracking gas oil to secure maximum gasoline yield

By varying the operation conditions indicated in the foregoing tabulations relating to distillation procedure, our improved apparatus operates as a cracking apparatus. As an example, for cracking gas oil to obtain a maximum yield of gasoline, we provide conditions of temperatures, pressure, etc., somewhat as indicated in the following tabulation:

60	Still No.	Still temp.	Vapor temp. leaving superheater (23)	Temp. at bottom of combination reaction chamber heat exchanger tower (17)	Temp. top of combination reaction tower (17)	Temp. bottom of bubble tower (52)	Temp. top of bubble tower (52)	Pressure in still lbs/sq. in. above atmo.	60
65	1	650° F.	850°	650°	575°	500°	350°	170lb or 70.	65
	2	675	875	675	585	510	360	160 or 60.	
	3	700	900	700	595	520	370	150 or 50.	
	4	725	925	725	605	530	380	140 or 40.	
	5	750	950	750	615	540	390	130 or 30.	
	6	775	975	775	625	550	400	120 or 20.	
	7	800	1,000	800	635	560	410	110 or 10.	
	8	825	1,025	825	645	570	420	100 or zero.	

uum is carried at 28 to 29 inches of mercury. In general, our purpose in using steam and/or vacuum in connection with distillation is to lower the vapor pressure of the desired cut so that it will be

The pressure drop between stills in pounds to the square inch or in pounds above atmospheric set forth above is merely illustrative. Instead of using a liberal supply of steam as in distillation,

we use a limited supply, for example, about 25 pounds to the barrel of charge treated, the restricted amounts of steam being utilized both in the liquid and above the surface thereof.

5 In order to produce a larger proportion of cracked kerosene from the gas oil and a smaller proportion of gasoline, the operating conditions above tabulated are adjusted to change the character of the product more particularly as derived from stills 6 and 7. The changes are indicated in the following tabulation, the temperatures, pressures, etc., therein being substituted in respect to corresponding stills for the temperatures and pressures set forth in the next 10 preceding tabulation:

20	Still No.	Still temp.	Vapor temp. leaving super-heater (23)	Temp. at bottom of combination reaction chamber heat exchanger tower (17)	Temp. top of combination reaction tower (17)	Temp. bottom of bubble tower (52)	Temp. top of bubble tower (52)	Pressure in still lbs/sq. in. above atmo.	20
25	6	760°	800°	760°	600°	540°	390°	100 or 20.	
	7	770	810	770	605	545	400	90 or 10.	
	8	780	820	780	610	550	410	80 or atmo.	25

In the operation of our apparatus as a cracking system with a gas oil or reduced crude charge and employing eight stills with corresponding towers, cracked kerosene is taken as an overhead vapor from the top of No. 4 bubble tower or fractionation unit operatively connected with still No. 4. At this particular stage of our method, we are able to recover a cracked kerosene having characteristics which permit it to qualify as commercial kerosene insofar as its carbon content compares with the carbon content of straight run kerosene produced by distillation from crude. In this respect our multiple still apparatus produces results superior to those attained by known types of single still apparatus employing cracking temperatures and pressures, but without our multiplicity of stills combined with reaction and heat exchange towers and fractionation bubble towers with vaporization, superheating and condensation in stages.

Combined distillation and cracking

Where it is desired to operate our system as a combined distilling and cracking apparatus, crude petroleum, for example, is charged into still No. 1, under the conditions of operation previously tabulated in connection with distillation runs. This produces straight run gasoline from the tops of towers No. 1 and No. 2 and straight run kerosene from the top of tower No. 3. By increasing the temperature gradient in the remaining stills and suitably adjusting the steam and pressure conditions therein, we produce cracked gasoline from the tops of towers Nos. 4, 5, and 6, cracked kerosene from the top of No. 7 and a light furnace oil from the top of No. 8.

Processing unfinished cracked gasoline

Some conditions of cracking, produce gasoline of too high a sulphur impurity content to permit sufficient purification by the usual purifying treatments. We are able to employ our processing apparatus as a treating system for re-running any kind of an unfinished cracked gasoline from whatsoever source. In so doing we vaporize a portion of the liquid charge in a stream and superheat the vapors in stages sufficiently to change the character of the gum and sulphur impurities, so that thereafter, the gas-

oline, upon being treated chemically or otherwise purified, is rated as finished gasoline.

When our apparatus or some portion thereof is operated for the purpose of treating a charge destined to yield wax distillate, such charge is redistilled in one or more stills in which a higher temperature is employed than that utilized in the still from which the charge, usually in the form of a heavy wax distillate, was originally produced. The vapor products of this reheat- 10 ing operation are superheated, thereby changing the character of the wax content so that when pressed it will be of a crystalline characteristic rather than amorphous. This operation may take place as a part of the continuous distilla- 15

tion from wax bearing crude under conditions previously noted or it may take place in all or any part of the stills of a battery operating for that purpose.

From the foregoing, it is clear that the advantages in operation associated with use of the apparatus hereinabove described, include its adaptability to the production of a wide range of ultimate products, either singly or simultaneously 35 from a great variety of raw materials ranging from crudes of different characteristics down through various grades of intermediates. This wide adaptability of the described apparatus, or apparatus equivalent thereto, is supplemented by 40 the economies capable of being effected in connection with its operation, as the conservation of heat, continuous use and simplified and flexible control.

In the employment, by this invention, of a plurality of still units assembled in a battery, with interconnecting and controlling devices, the pressure may be varied as to different stills in a progressively increasing or decreasing gradient; or it may be varied in any other way required to secure 50 any particular product or to effectively treat any given character of raw material. It will be apparent that our improved method and apparatus also present a wide range of flexibility in the control of all critical operating factors not only in 55 the stills but also in the condensation and cooling devices associated therewith. The importance of this will be recognized in its relation to the making of products which can only be secured in a pure or relatively pure state by condensation from the 60 vapor phase under particular conditions of temperature and pressure.

We claim as our invention:

1. The process of distilling hydrocarbon oil to produce several fractions including lubricating 65 oils as overhead distillates which includes passing said oil into and through a plurality of enlarged zones arranged in series, heating the oil in the first zone of the series to about 450° F., obtaining vapors and unvaporized oil in each of 70 said zones and passing the latter successively from zone to zone and heating said unvaporized oil to successively higher temperatures, the temperature of the oil in the last zone being about 700° F., operating at the beginning under ap- 75

proximately atmospheric pressure, distilling the liquid with steam toward the last stages of the distillation, finally discharging unvaporized liquid from the last zone, separately superheating vapors produced in each enlarged zone to successively higher temperatures, the vapors produced in the first enlarged zone being superheated to about 650° F. and the vapors produced in the final zone being superheated to about 800° F., separately

fractionating the streams of superheated vapors and condensing overhead fractions as products of the process.

2. The process of claim 1 including the step of operation under vacuum toward the last stage of 5 the distillation.

ARTHUR J. SLAGTER.
CHARLES W. MACKAY.
